APPARATUS FOR RETAINING CONTACT
MASSES IN TUBULAR ELEMENTSMaynard F. Perkins, Chicago, Ill., assignor to
Universal Oil Products Company, Chicago, Ill.,
a corporation of Delaware

Application July 12, 1939, Serial No. 283,989

5 Claims. (Cl. 23—288)

This invention relates to a simple and inexpensive device for releasably supporting a mass or column of granular contact material in a tubular element of a reactor or the like.

Many processes for the refining treatment or conversion of hydrocarbons, as well as a wide variety of processes common to the chemical industry generally, employ one or more beds of contact or filtering material, such as charcoal, fuller's earth and the like or granular material possessing catalytic activity, through which a stream of fluid to be treated or converted is passed upwardly or downwardly. In many such instances it is common practice to employ a reactor or filter chamber comprising one or more elongated tubular elements within which the contact mass is disposed and, to give access to the interior of the tubular element or elements for inspection, cleaning, replacement of the bed of contact material, etc., a header or other suitable terminal fitting is provided at one or both ends of the tubular element or elements, the terminal fitting being provided with a port opposite the end of the tube and a removable closure member for said port such as a ground joint or screw plug, bolted cover plate or the like.

The improved device provided by the invention is intended for use in conjunction with reactors, filter chambers and the like of the type above outlined and serves the useful purpose of releasably retaining the column or bed of contact material in the tubular element or individual tubular elements of the apparatus in such a manner that it will not be unintentionally dropped from the tube or tubes when the closure member is removed from the port, but is readily accessible through the port when the closure member is removed therefrom.

The features of the invention can best be explained with reference to the accompanying diagrammatic drawing in which:

Fig. 1 is a longitudinal section of the lower portion of a reactor tube or the like terminating in a fitting of the type above referred to and incorporating a device of the type provided by the invention for retaining a bed of contact material within the tube.

Fig. 2 is a view similar to Fig. 1 with the closure means removed from the fitting and the supporting device in a position to drop the bed of contact material from the tube.

Fig. 3 is a plan view of the contact mass supporting device designated by the reference numeral 9 in Figs. 1 and 2.

Referring to the drawing, the tube 1 which

contains a bed of granular contact material 2 is in this particular instance rolled at its lower end into a terminal fitting 3 having a threaded port 4 in the side wall thereof through which fluid to be treated in the bed of contact material may be introduced into the fitting and flow therefrom upwardly through the tube or through which the treated materials discharged downwardly from the bed of contact material in the tube may be removed. A tapered plug port 5, 10 preferably of somewhat larger minimum diameter than the external diameter "D" of the tube and, in any case, of somewhat larger minimum diameter than the internal diameter "d" of the tube is provided in the end of fitting 3 directly 15 opposite the lower end of the tube and aligned with the vertical axis of the tube. Beneath the tapered plug port 5 and communicating therewith a screwed plug port 6 is provided. The closure means for the lower end of the fitting 20 comprises a tapered plug 7, the tapered face of which is ground to a seat with the tapered surface of the plug port 5, and a screwed plug 8 which bears against the tapered plug and retains it in position.

The specific form of terminal fitting here illustrated or any other conventional form may be employed within the scope of the invention so long as an access port with closure means therefor is provided directly opposite the end of the 30 tube and is at least as large in diameter as the internal diameter of the tube and so long as the fitting is provided with a ledge, protruding lug, recess or the like upon which the end of the removable member 9 for retaining the bed of contact material in place may firmly rest, as will be presently described.

In this particular instance, a ledge or shoulder 10 is provided above the tapered plug port 5 and the lower end of bar or rod 11 of member 40 9 bears against and is supported from this ledge when member 9 is in position to retain the bed of contact material within the tube, as illustrated in Fig. 1. The upper end of bar or rod 11 is attached by welding or by any other desired manner, not illustrated, to the central portion of disc or plate 12 which is provided with a plurality of perforations 13 to permit the passage of incoming reactants into the bed of contact material or the passage of outgoing products from the bed of contact material, as the case may be. The perforate disc or plate 12 is somewhat smaller in diameter than the internal diameter "d" of the tube so that it will readily 50 55

pass into and out of the tube and through the plug ports in fitting 3.

When desired, particularly in case a substantial quantity of the granules, comprising the bed of contact material, are of relatively small size and are of such form that they might tend to plug the perforations 13 provided in disc 12, a reticulate member such as a screen or wire fabric indicated at 14 is provided over the upper surface 10 of the perforate disc and, when desired, may be secured thereto by tack welding or in any other desired manner. As an alternative to the use of screen 14, when required, one or more relatively shallow beds or layers of inert material 15 such as gravel or rock or spherical shapes of glass, baked clay or the like, such as marbles, may be provided between the perforate disc 12 and the bed of contact material to prevent loss of the latter through the perforations of the disc. This is now a well known expedient and is not illustrated in the drawing.

In employing the releasable retaining device of the invention; before tube 1 is filled with contact material and with plugs 7 and 8 removed 25 from fitting 3, member 9 is inserted through the plug ports into the lower end of the tube with bar or rod 11 in a substantially vertical position such as illustrated in Fig. 2 and this bar or rod 11 is then moved into engagement with ledge 10, 30 as illustrated in Fig. 1, the angular relation of bar 11 and disc 12 being such that the disc is in a substantially horizontal position, as shown in Fig. 1, when bar 11 rests on ledge 10. The tube may then be filled with contact material and the 35 plugs 7 and 8 inserted in the fitting at any time after member 9 is in place.

Since member 9, in cooperation with the portion of the fitting upon which it rests, supports the bed of contact material independent of the 40 removable plugs 7 and 8, the latter may be removed at any time for inspection or the like without disturbing the bed of contact material and, when it is desired to replace the latter, the plugs may be removed from the fitting and suitable 45 receptacles for catching the contact mass may be placed beneath the open plug ports before the mass is released from the tube.

To facilitate the removal of member 9, a suitable opening 15 is preferably provided adjacent 50 the lower end of bar 11 by means of which the bar may be grasped with a suitable hook or the like, not illustrated, through the open plug ports and pulled from ledge 10, thus allowing member 9 and the bed of contact material, which it has 55 been supporting, to drop through the open plug ports.

I claim as my invention:

1. In an apparatus of the class described, a releasable supporting element comprising a perforate metal disc and an elongated arm fixedly 60

secured to and extending from the central portion of said disc at an oblique angle to the plane thereof, the free end of said arm terminating in a surface substantially parallel to that of the disc.

2. In an apparatus of the class described, a 5 releasable supporting element comprising a perforate metal disc and an elongated arm fixedly secured to and extending from the central portion of said disc at an oblique angle to the plane thereof, the free end of said arm terminating in 10 a surface substantially parallel to that of the disc, and a reticulate member of relatively small mesh in relation to the perforations of said disc disposed over the free surface of said disc.

3. In an apparatus of the class described, a 15 releasable supporting element comprising a perforate metal disc and an elongated arm fixedly secured to and extending from the central portion of said disc at an oblique angle to the plane thereof, the free end of said arm terminating in 20 a surface substantially parallel to that of the disc, and said arm being provided with an opening therethrough adjacent said end.

4. In combination with an elongated substantially vertically disposed tubular member adapted 25 to contain a mass of granular contact material and having a terminal fitting at its lower end provided with a port directly opposite the tube and closure means for said port, means insertable into the terminal fitting and lower end of the 30 tube through said port and adapted to retain said mass of contact material within the tube independently of the closure means for said port, said means being supported at one end thereof on a portion of the terminal fitting other than the 35 closure means for said port and being accessible for release from its retaining position when the closure means for said port is removed.

5. In combination with an elongated substantially vertically disposed tubular member adapted 40 to contain a mass of granular contact material, a terminal fitting at the lower end of said tube provided with a port in axial alignment with said tube, closure means for said port, a perforate disc of slightly smaller diameter than the internal diameter of the tube, an arm fixedly secured to and extending from the central portion of the disc and depending therefrom at an oblique angle to the plane of the disc, said disc and arm being adapted to pass through said port in the 45 terminal fitting and enter the lower end of the tube, and an internal shoulder in said terminal fitting for firmly supporting the free end of said arm when said perforate disc is in substantially horizontal position within the tube, the said arm 50 and disc being thereby adapted to support said mass of contact material, disposed above the perforate disc, independent of the position of said fitting closure means.

MAYNARD F. PERKINS. 60
